By S. A. Janowicz.
Attorney.

UNITED STATES PATENT OFFICE

ALFRED H. WEISS, OF WILMETTE, ILLINOIS, ASSIGNOR TO KELLOGG SWITCHBOARD AND SUPPLY COMPANY, OF CHICAGO, ILLINOIS, A CORPORATION OF ILLINOIS

IGNITION AND LIGHTING SWITCH

Original application filed May 24, 1920, Serial No. 383,675, now Patent No. 1,563,411, dated December 1, 1925. Divided and this application filed January 27, 1922. Serial No. 532,142.

My invention relates to electrical switches in general and has to do more particularly with so-called combination lighting and ignition switches, such as are used for controlling the lighting and ignition circuits of an automobile or the like. An object of my invention is to produce a device of the above character which contains novel features of construction and combination of parts, all of which produce a simple, efficient and economical switch structure.

A feature of my invention is an improved construction of the rotor element, which rotor element is operatively associated with contact springs to establish the desired different circuit combinations, as the rotor element is actuated.

The above feature, as well as others, consists of novel details of construction and combination of parts hereinafter more particularly pointed out in the ensuing specification and appended claims.

This application is a divisional application of my application S. N. 383,675, filed May 24, 1920 and issued as Letters Patent No. 1,563,411, on December 1, 1925.

For a more complete understanding of my invention, reference may be had to the accompanying drawings in which like reference characters, in the several views, denote like parts, and in which:

Fig. 1 is an interior face view of a switch structure embodying the rotor element of my invention, certain parts of the switch structure being omitted to clearly illustrate parts associated with the rotor element.

Fig. 2 is a sectional view of the switch structure with which the rotor element of my invention is associated.

Fig. 3 is a vertical section of the rotor element illustrating its construction; and

Fig. 4 is a vertical section of the rotor element taken at right angles to that of Fig. 1.

Referring now in general to my invention and referring to Fig. 1, I illustrate the rotor element of my invention in association with a switch structure which comprises two units M and L each of which is provided with a rotor element in association with contact springs (not shown). A locking mechanism

which consists preferably of a standard tumbler cylinder lock T and which controls a sliding locking plate LP cooperates with the rotor elements as will be hereinafter more fully described.

Referring now more in detail to my invention as illustrated, it comprises, preferably, a mounting plate 2 made of any suitable insulating material, such as bakelite, and having a stud 4 fastened to it in any suitable manner, as by means of the nut 5, which nut 5 has screw-threaded engagement with the threaded portion of the stud 4, which extends beyond the rear face of the plate 2. The plate 2 is provided with a peripheral ridge 2², extending upwardly from the plate proper and is also provided with a flange upon which the cover-cap of the device rests.

The unit L and the unit M are each provided with a rotor element, and as both are similar in construction, a description of one of them will suffice. The rotor element associated with the unit L comprises a supporting stud 32, a holding disc 33 for holding the unit L in its different positions, as will be more fully hereinafter described, a washer 34, a retaining member 35, a sleeve 36 of suitable insulating material, insulation washers 37, 38 and 39, cams 40 and 41 of suitable insulating material, a cam 42 of suitable conducting material, and a washer 43, which members are all supported upon the stud 32. The disc 33 is provided with an orifice of a size to permit its being slipped over the body portion 44 of the stud 32 and when in place rests against the flanged portion 45 of the stud 32. The insulating sleeve 36 is provided with an orifice of a size to permit its being slipped over the body portion 44 of the stud 32, the said sleeve when in place rests against the member 33. The washer 34 is provided with an orifice of a size to permit its being slipped over the insulating sleeve 36, and the retaining member 35 is also provided with an orifice of a size to permit it being slipped over the insulating sleeve 36. Washers 37 and 38, cams 40 and 41 and cam 42 are also provided with orifices to permit them being slipped over the sleeve 36. Washer 37 is placed between

55

60

65

70

75

80

85

90

95

100

the retaining member 35 and insulation cam 40, and the metal cam 42 when in place rests between the said insulating cams 40 and 41 with the insulating washer 38 resting between the said metal cam 42 and the cam 40. 5 The washer 43 and insulating washer 39 are provided with orifices of a size to permit them being slipped over the body portion 44 of the stud 32, the said body portion 44 extends slightly beyond the face of the washer 43 for purposes as will presently be described. To hold the members 35, 37, 38, 10, 39, 40, 41, 42 and 43 in fixed relation with each other and the stud 32, I provide the retaining member with a lug 46 which is bent at right angles to the plane of the member proper, the said lug 46 extending through openings 47 in the washer 37 and cam 40, its end resting against the insulating washer 38 to insulate the member 35 from the cam 42. 15 A lug 48 integrally formed with the retaining member 35 and diametrically opposite the lug 46 is bent at right angles to the plane of the retaining member proper, the said angular portion 49 resting in a notch 50 cut in the periphery of the holding member 33. The end 51 of the lug 48 is bent parallel to the plane of the member proper and rests in a notch 52 cut in the flanged portion 45 of the stud 32. 20

The metal cam member 42 is provided with pins 53 and 54 diametrically opposite and suitably secured thereto, which are adapted to cooperate with the insulating cams 40 and 41 so as to hold the cams 40, 41 and 42 in fixed relation with each other. The pins 35 and 53 and 54 protrude beyond both faces of the cam member 42, and their ends 53' and 54' extend into suitable orifices 55 and 56 in the cam member 41, the said ends of the pins abutting against the insulating washer 39 to insulate the said pins from the washer 43. The other protruding ends 53² and 54² of pins 53 and 54 extend through suitable orifices 57 and 58 in the cam member 40, the ends of the said pins 53 and 54 abutting against the insulating washer 37 to insulate them from the retaining member 35. When the members 33, 34, 35, etc., are in place upon the stud 32, the body portion 44 of the stud 32 protrudes beyond the face of washer 43 and this extended portion is upset or spun over, securing the said members upon the said stud 32 against displacement, and the lugs 46 and 48 of the retaining member 35 in association with the pins 53 and 54 of the cam member 42 prevent the said members 33, 34, 35, etc., from rotating on the stud 32 and hold them in fixed relation with each other. 50

The stud 32 is provided with a suitable opening for fitting over the end of the stud 4 to bring the cams 40, 41 and 42 into operative relation with certain of the contact springs secured to the plate 2, and is of a size to permit the rotation of the switch unit L on the

stud 4. The insulation cams 40 and 41 and the metal cam 42 are adapted to engage and disengage the contact springs secured to the plate 2 and associated with the switch unit L for closing and opening the circuits controlled by the said switch unit L. When the rotor element of switch unit L is rotated to its different positions, certain of the contact springs associated with said rotor element will be in contactual engagement with the insulation cams 40 and 41 to open certain circuits, while the other of said contact springs will have contactual engagement with the metal cam 42 to close certain circuits controlled by the switch unit L. 70 75

The holding member 33 of the unit L is in the form of a notched or toothed disc or star wheel, and to cooperate with the discs or star wheels 33 and 33' to yieldingly hold the units L and M, respectively, in any of their operated positions, I provide a holding device H which comprises a centrally pivoted member 80, which carries rotatable rollers 81 and 82 in its bifurcated ends, said rollers 81 and 82 operating in connection with their corresponding discs or wheels 33' and 33 of the unit M and the unit L. The member 80 is pivotally supported at its center by a stud 83, which is suitably fastened to the mounting plate 2 by means of a nut 84, which nut 84 has screw-threaded engagement with the threaded portion of the stud 83. A spring 85 for yieldingly holding member H against the discs or wheels 33 and 33' of the switch units L and M, is provided, and a clamping bracket 86 secured to the mounting plate 2 by means of a screw 87 is provided with an angular extension 88 which rests in a notch 89 cut in the end 90 of the spring 85 to secure the spring 85 to the mounting plate 2 against 90 displacement. The angular extension 88 of the bracket 86 rests in a notch 91 in the peripheral ridge 2² to prevent the said bracket from turning. When one of the switch members is operated, the teeth of its disc are rotated against its associate roller, due to the action of the spring 85, and as the disc or star wheel advances the roller acts upon the next notch so as to give a snap action to the switch member and at the same time hold the actuating members of the switch in place. 100 105 110 115

A locking arrangement is provided whereby the units L and M may be locked in their different positions. I provide a pin-tumbler cylinder lock T cooperating with a sliding locking plate LP. The cylinder lock comprises the usual lock case 95, which lock case is provided with the usual tumbler extension 96, and rotatably mounted in the casing 95 is the key barrel or cylinder 97. The key barrel 97 extends rearwardly from the casing 95, and this rearwardly extending portion 98 rests in a pocket or depression 99 in the mounting plate 2. The lock casing 95 is also provided with a pair of lugs 100, prefer- 120 125 130

ably integrally formed therewith, the said lugs 100 resting in a notch 102 cut in the ring portion 2² of the mounting plate 2, which ring portion 2² is formed by the inner circumferential edge of the cup-shaped portion of the plate 2 and the outer circumferential edge of the plate 2. The lock barrel 97 resting in the pocket 99, which forms a seat for the said barrel 97, in conjunction with lugs 100, which rest in the notch 102, centers said lock and prevents rotation of the same in the pocket 99 when the key 103 of the lock is turned. The sliding locking plate LP, which is provided for locking the units L and M so that they cannot be operated, consists of a plate 104 provided with elongated slots 105 and 106, through which the studs 3 and 4 extend. The plate 104 is also provided with a U-shaped notch 107 of a size to permit it to span the lock barrel 97 which rests in the pocket 99 in the mounting plate 2. The slots 105 and 106 and the U-shaped notch 107 in association with the studs 3 and 4 and the key barrel 97, form guiding means for the plate 104 when the said plate is moved to lock or unlock the switch units L and M, as the case may be. To permit movement of the plate 104 when the key 103 is rotated to lock or unlock the switch units L and M, I provide a pin 108 which is secured to the rearwardly extending portion 98 of the key barrel 97, the said pin 108 cooperating with a pin 109, which is secured to the sliding plate 104 in the desired manner. The plate 104 is also provided with angular extensions 110 and 110', which extensions are preferably integrally formed with the said plate 104, the said extensions 110 and 110' cooperating with the discs 33' and 33 of the switching units M and L.

I have preferably arranged the unit M so that it can only be locked in its normal or inoperative position, and I, therefore, provide a single slot 33² in the disc or wheel 33', while the disc or wheel 33 of the unit L is provided with three slots 33³, 33⁴ and 33⁵, whereby the unit L may be locked in its normal or two of its three operative positions. No slot is provided for the second operative position of the switch unit L, so that when the unit L is in its second position and an attempt is made to lock the units after the unit M is restored to its inoperative position, the key 103 can only be turned part way and the operator is at once notified that the switch lever must be turned back to one of its other operative or normal positions to enable him to lock the switch. The discs 33 and 33' of the units L and M are provided with lugs 111 and 112, 113 and 114 to limit the movements of the switch units L and M in their normal and farthest advanced positions. The lugs 111 and 113 of the disks or wheels 33 and 33', respectively, limit the movement 65 of the switch units L and M in their normal

position by engaging the forward ends of the angular extensions 110' and 110 of the sliding locking plate 104, and the lugs 112 and 114 of the switch units L and M are limited in their farthest advanced positions by the engagement of the said lugs 112 and 114 with the forward ends of the angular extensions 110' and 110 of the sliding locking plate 104.

In Fig. 1 I show the locking mechanism operated to lock the switching units L and M against movement, but also showing the mechanism at normal. To lock the switch units L and M, the key 103 of the lock T is inserted and turned to the right until the pin 108 in the key barrel 97 engages the pin 109 in the plate 104. Continued rotation of the key 103 of the lock T moves the plate 104 in an upward direction into the position shown in Fig. 1. The extensions 110 and 110' enter the slots 33² and 33³ of the switching units M and L, respectively, preventing the movement of said units. To unlock the switch units L and M, the key is turned to the left until the pin 108 engages pin 109 to move the plate 104 in a downward direction, and this downward movement of the sliding locking plate 104 withdraws the extensions 110 and 110' from the slots 33² and 33³.

The locking plate 104 is held in its locked position against the action of the pin 108 in the end of the key barrel 97. As the barrel is turned in a lock-wise direction by the key 103 the pin 108 engages the pin 109 secured to the locking plate 104 and moves the plate 104 in its locked position as illustrated in Fig. 1. When the key 103 is withdrawn the pin tumblers move down under the influence of springs and enter the barrel 97 to lock the barrel against rotation as is well understood. The pin 108 in the barrel 97 being in engagement with pin 109 of the lock plate 104 holds the plate 104 in its locked position against the action of gravity as is readily apparent from the above description. A flat spring 116 having its one end secured between the member 80 and the mounting plate 2 by means of the stud 83; and its free end engaging the sliding locking plate 104 produces a frictional action on the plate 104 as it is moved to its locked or unlocked position. A cover or casing 117 is provided for enclosing the mechanism, and is provided with suitable openings to permit the passage of the studs 3 and 4. Handles are secured to the studs 3 and 4 in any suitable manner, the said handles being grasped by the operator to move the switching units L and M to their different operative positions. The cover 117 is also provided with a suitable opening 121 of a size to permit the passage of the forward end or head 122 of the key barrel 97, this opening 121 also forming a bearing for the head 122 of the key barrel 97 when it is rotated by the key.

While I have described a certain form of invention, and while I have described it in connection with a particular type of switch it is to be understood that changes and modifications will readily suggest themselves to those skilled in the art, and I, therefore, do not wish to be limited to the exact structure, as shown, but aim to cover all such changes and modifications as come within the spirit and scope of the appended claims.

What I claim as new and desire to secure by United States Letters Patent is:

1. A rotor device of the character described including a mounting plate, a non-rotatable supporting member secured to said mounting plate, a supporting stud rotatably carried by said non-rotatable supporting member, a star wheel carried by said stud, a circuit closer carried by said stud, a pair of insulating cams located on each side of said circuit closer, means for preventing rotation of said cams and circuit closer relative to each other, a member securing said star wheel and said circuit closer to said stud to prevent said star wheel and circuit closer from rotating relative to said stud, means cooperating with said star wheel for yieldingly holding said rotor in position, and locking means adapted to engage said star wheel to prevent any rotation of said rotor.

2. A rotor device of the character described including a mounting plate, a non-rotatable supporting member secured thereto, a rotary shaft carried by said non-rotatable supporting member, a star wheel carried by said shaft, a circuit controller including cams of conducting material and cams of insulating material carried by said shaft, a member for preventing rotation of said circuit controller relative to said cams, a second member for preventing relative rotation of said cams and star wheel and securing the same to said rotary shaft, means cooperating with said star wheel for yieldingly holding said rotor in position, and locking means adapted to engage said star wheel to prevent any rotation of said rotor.

3. A rotor device of the character described including a rotary shaft, a contact controller carried thereby including a cam of conducting material and a pair of cams of insulating material, a member securing said cams together, a second member securing the said cams to said rotary shaft, and means for rotatably supporting said rotor element.

4. A rotor device of the character described including a shaft, a pair of cams of insulating material and one of conducting material adapted to be fitted onto said shaft, means for holding said cam on said shaft, a member for preventing rotation between said cams of insulating material and said cam of conducting material, a second member for preventing rotation of one of said cams relative to said shaft, a stud for rotatably sup-

porting said rotor and means for yieldingly holding said rotor in position.

5. A rotor device of the character described including a rotary shaft, a member provided with serrations carried by said shaft, a pair of cams of insulating material, and a cam of conducting material carried by said shaft, means for preventing rotation of the cams of insulating material relative to the cam of conducting material, means for preventing rotation of said cams and said member provided with serrations relative to said shaft, and means cooperating with said serrated member for yieldingly holding said rotor in position.

6. A rotor device of the character described including a rotary shaft, a member provided with serrations carried by said shaft, a pair of cams of insulating material, and a cam of conducting material carried by said shaft, means for preventing rotation of the cams of insulating material relative to the cam of conducting material, means for preventing rotation of said cams and said member provided with serrations relative to said shaft, means for insulating said cam of conducting material from said rotary shaft, and means cooperating with said serrated member for yieldingly holding said rotor in position.

7. A rotor device of the character described including a rotary shaft, a member provided with serrations carried by said shaft, a pair of cams of insulating material, and a cam of conducting material carried by said shaft, means for preventing rotation of the cams of insulating material relative to the cam of conducting material, means for preventing rotation of said cams and member provided with serrations relative to said shaft, means for insulating said cam of conducting material from said rotary shaft, means for insulating said cam of conducting material from said device provided with serrations, and spring controlled means cooperating with said serrated member for yieldingly holding said rotor in position.

8. A rotor device of the character described including a rotary shaft, a member provided with serrations carried by said shaft, a pair of cams of insulating material, and a cam of conducting material carried by said shaft, means for preventing rotation of the cam of insulating material relative to the cam of conducting material, means for preventing rotation of said cams and said member provided with serrations relative to said shaft, means for insulating said last member from said cam of conducting material, and spring controlled means cooperating with said serrated member for yieldingly holding said rotor in position.

9. A rotor device of the character described including a rotary shaft, a device provided with serrations carried by said shaft,

a pair of cams of insulating material and a cam of conducting material carried by said shaft, means for preventing rotation of the cams of insulating material relative to the cam of conducting material, means for preventing rotation of said cams and said member provided with serrations relative to said shaft, means for insulating said cam of conducting material from said rotary shaft and said device provided with serrations, and spring controlled means cooperating with said serrated member for yieldingly holding said rotor in position.

Signed by me at Chicago, in the county of Cook and State of Illinois, this 20th day of January, 1922.
